UNITED STATES PATENT OFFICE.

CHARLES B. ULRICH, OF JAMESTOWN, NEW YORK.

INDEXING DEVICE.

1,319,816.

Specification of Letters Patent. Patented Oct. 28, 1919.

Application filed December 16, 1918. Serial No. 266,873.

To all whom it may concern:

Be it known that I, CHARLES B. ULRICH, a citizen of the United States, residing at Jamestown, in the county of Chautauqua and State of New York, have invented a certain new and useful Improvement in Indexing Devices, of which the following is a specification.

My invention relates to an improved form of indexing device for use in filing cabinets, by means of which a name slip or other indexing legend may be securely held in desired position in a file and by which the said slip is clamped in position when in use by the spring action of part of the device and readily removable when desired. The indexing slip when in use is protected from injury and the device may conveniently be employed as a guide tab in the file and when so employed constitutes a reinforcing means for the edge of the guide card with which it may be employed.

My invention will best be understood by reference to the accompanying drawing showing a preferred embodiment thereof, in which—

Figure 1 shows in perspective view a part of a guide card with the indexing device in place thereon,

Fig. 2 is a sectional view of the parts shown in Fig. 1 taken along the lines 2—2, and

Fig. 3 shows in a view similar to Fig. 2 the position of the parts to release the index slip, the parts in Fig. 2 being in the position assumed to clamp the slip securely in place when in use.

Similar numerals refer to similar parts throughout the several views.

As shown in the drawings the guide card 10 has secured thereto a metal plate 11 by means of rivets 12 and said plate is extended above the upper edge of the card 10 and bent slightly at its upper edge toward the front of the guide card. The plate 11 extends well down on the body portion of the card 10 so that the rivets 12 extend through the body portion of the card as a result of which the plate is securely held to the card, whether the card is provided with a projecting tab 13 or not thus avoiding the danger when the tab is used, of breaking off the tab by repeatedly handling the indexing device. The upper edge of the card 10 has secured thereto by means of rivets 14 a sheet of transparent elastic material 15

which may be celluloid or the like and which is given a cylindrical conformation at its mid-portion above the edge of the card to inclose the upper edge of the metal plate, 60 said transparent sheet being of substantially the width of said plate. Said sheet is conformed so that when not subjected to external force it rests snugly at its mid-portion against the rear side of the upper portion of the plate 11. An index slip 16 of thin flexible material such as paper and having thereon any desired indexing legend is located within the cylindrical portion of the transparent sheet 15 with its rear edge between said sheet and the rear face of the upper portion of the plate 11 as a result of which the spring action of the sheet 15 clamps the slip in place against the rear face of the upper portion of the metal plate. 70 The slip is preferably of a width such that its lower edge rests against the upper edge of the card 10 and in this position the slight spring action of the slip causes it to assume a circular conformation within the 80 sheet 15 resting against the inner surface of the mid-portion thereof. The legend on the slip is preferably placed so that it may be best read through the transparent sheet from above and in front of the card 10 85 when the latter is in substantially vertical position, assuming that the indexing device is employed in connection with a vertical file. For other types of file the same indexing device may be used by properly positioning the legend on the indexing slip. 90 In any event it will be observed that for any special case as for example using the device in a vertical file the legend may always be placed at the same distance from 95 the lower edge of the indexing slip and brought into a desired line of sight since the engagement between the lower edge of the slip and the upper edge of the card 10 places the slip in definite angular position in the 100 cylindrical portion of the sheet 15.

When it is desired to remove the indexing slip from the device the sheet 15 is pressed rearwardly at its cylindrical portion, or in the direction indicated by the 105 arrow in Fig. 3 which moves the rear portion of the upper part of the formed sheet rearwardly from engagement with the rear face of the upper portion of the plate 11 thus leaving a clearance between the sheet 110 and plate and freeing the indexing slip so that the latter may be readily removed

from within the cylindrical portion of the sheet. In this manner the indexing slip may be readily inserted and removed from the indexing device as desired and yet be securely clamped in position in the indexing device when in use. It will be observed that when in use the indexing slip is entirely covered and protected from wear, dirt and injury by the inclosing sheet and that the metal plate through which the rivets 14 extend, reinforces and protects the edge portion of the card 10 so that the tendency to tear the card resulting from using the indexing device in a file is reduced to a minimum.

While I have shown my invention in the particular embodiment above described, I do not however limit myself to this exact construction as I may employ any equivalents thereof known to the art at the time of the filing of this application without departing from the scope of the appended claims.

What I claim is:

1. In an indexing device, the combination of a support, a plate secured to the support and projecting from one edge thereof, and a transparent sheet of spring material folded to inclose the projecting edge of said plate and having its edge portions secured to said support, said sheet by its spring action pressing against the projecting portion of said plate to clamp an index slip between said sheet and said plate when said slip is in position in the folded portion of said sheet.
2. In an indexing device, the combination of a support, a plate secured to the support and projecting from one edge thereof, and a transparent sheet of spring material folded to inclose the projecting edge of said plate and having its edge portions secured to said support, said sheet by its spring action pressing against the projecting portion of said plate to clamp an index slip between said sheet and said plate when said slip is in position in the folded portion of said sheet, there being a clearance between said plate and said sheet within the folded portion of said sheet adjacent the clamping portion of said sheet, whereby pressure on said folded portion moves said clamping portion of said sheet away from said plate to permit the ready insertion and removal of an index slip.
3. In an indexing device, the combination of a guide card, a metal plate projecting from one edge of said card, fastening devices securing said plate to the body portion of said card, and a sheet of celluloid folded to inclose the projecting edge of said plate, fastening devices extending through the edges of said sheet and also through said card and said plate to hold the parts together, said sheet being conformed to rest snugly against

the rear face of the projecting portion of said plate when held in place by the last named fastening devices, there being a clearance between the edge of the projecting portion of said plate and the folded portion of said sheet in front of said projecting portion, whereby pressure rearwardly on the folded portion of said sheet separates said sheet from the rear face of the projecting portion of said plate to permit the ready insertion and removal of an index slip within the folded portion of said sheet, the edge of said index slip when said slip is in place in the folded portion of the sheet being between the rear face of said projecting portion and said sheet to securely clamp said slip in place.

4. In an indexing device, the combination of a guide card, a metal plate projecting from one edge of said card, fastening devices securing said plate to the body portion of said card, and a sheet of celluloid folded to inclose the projecting edge of said plate, fastening devices extending through the edges of said sheet and also through said card and said plate to hold the parts together, said sheet being conformed to rest snugly against the rear face of the projecting portion of said plate when held in place by the last named fastening devices, there being a clearance between the edge of the projecting portion of said plate and the folded portion of said sheet in front of said projecting portion, whereby pressure rearwardly on the folded portion of said sheet separates said sheet from the rear face of the projecting portion of said plate to permit the ready insertion and removal of an index slip within the folded portion of said sheet, the edge of said index slip when said slip is in place in the folded portion of the sheet being between the rear face of said projecting portion and said sheet to securely clamp said slip in place, said folded portion being of cylindrical conformation and related to said card to constitute the edge of said card a gage for the positioning of said slip and the projecting edge of said plate being conformed to fit the inner surface of the cylindrical portion of said sheet.

5. In an indexing device, the combination of a flat support, a plate secured to the support adjacent one edge thereof, and a transparent sheet of spring material folded to inclose the edge of said plate and having its edge portions secured to said support, said sheet by its spring action pressing against the edge portion of said plate to clamp an index slip between said sheet and said plate when said slip is in position in the folded portion of said sheet.

6. In an indexing device, the combination of a flat support, a plate secured to the support adjacent one edge thereof, and a trans-

parent sheet of spring material folded to inclose the edge of said plate and having its edge portions secured to said support, said sheet by its spring action pressing against the edge portion of said plate to clamp an index slip between said sheet and said plate when said slip is in position in the folded portion of said sheet, there being a clearance between said plate and said sheet within the folded portion of said sheet adjacent the clamping portion of said sheet, whereby pressure on said folded portion moves said clamping portion of said sheet away from said plate to permit the ready insertion and removal of an index slip.

7. In an indexing device, the combination of a flat support, a metal reinforcing plate secured to the edge portion of the support, and a transparent sheet of material folded to inclose the edge of said plate and having its edge portions secured to said support, the folded portion of said sheet being open and separated from the edge of said plate and said support to receive within it an index slip. 20

In witness whereof, I hereunto subscribe my name this 26th day of November, A. D. 1918. 25

CHARLES B. ULRICH.
